UNITED STATES PATENT OFFICE.

JOSEPH W. COLLINS, OF PAWTUCKET, RHODE ISLAND.

BOBBIN AND WHIRL.

No. 891,814.

Specification of Letters Patent.

Patented June 30, 1908.

Application filed February 20, 1906. Serial No. 302,015.

To all whom it may concern:

Be it known that I, JOSEPH W. COLLINS, a citizen of the United States, residing at the city of Pawtucket, in the county of Providence and State of Rhode Island, have invented certain new and useful Improvements in Bobbins and Whirls, of which the following is a specification, reference being had therein to the accompanying drawing.

10 This invention relates to improvements in bobbins or cops and has for its object to provide means whereby the bobbin may be dropped over the spindle to engage and be rotated by the whirl, while said whirl is

15 rapidly revolving.

In the operation of the ordinary spinning or twisting machine it is found necessary, for various reasons known to the art, to very often remove the bobbin from the spindle 20 during the operation of spinning or twisting. In replacing the bobbin in position thereon, the rapidly revolving whirl has always had to be slowed down or stopped before said bobbin could be made to properly engage the same. To accomplish this purpose a friction 25 brake was used on the whirl which held the same from rotating while the bobbin was being connected thereto, causing the driving band to slip around the whirl while being 30 thus held.

To obviate the stopping of the whirl I have formed a set of comparatively fine tapering teeth all around the upper face of the body of the whirl, and I have also provided a metal 35 plate with a set of corresponding teeth on one face, which plate is set into the lower end of the bobbin, and securely held therein, and by this construction the bobbin may be dropped over the spindle onto the rapidly 40 revolving whirl and these teeth will engage each other and cause the said bobbin to rotate, without first being obliged to slow down the whirl.

The invention is fully set forth in this 45 specification and more particularly pointed out in the appended claims.

In the accompanying drawings: Figure 1— is an elevation of the bobbin showing the lower portion broken away and the toothed 50 plate secured therein. Fig. 2— is a central sectional view of the whirl showing the plurality of comparatively fine tapering teeth formed on the upper face thereof. Fig. 3— 55 is a detail showing the plate having teeth on its lower face for engaging the whirl and

spurs on its upper face by which said plate is secured to the wooden bobbin.

Referring to the drawings, the bobbin 1 is ordinarily and preferably formed of wood or other light material, and heretofore it has been customary to cut slots through the lower end of this bobbin to receive corresponding projections on the upper face of the whirl, but owing to the size and shape of these projections and slots the whirl had to be first stopped from rotating before the bobbin could be connected thereto.

In my improved construction I have counterbored the lower end of this bobbin at 5 to receive the plate 2, which plate is preferably made of metal of considerable thickness and is counterbored at 3 to provide a downwardly projecting rim. This plate is also provided on the lower face of said rim with a plurality of comparatively fine tapering 75 teeth formed all around the edge of the same. Projecting upward from the upper face of this plate is a plurality of integral spurs 4—4 which are disposed at points between the periphery of said plate and the bore thereof 80 adapted to be forced into the wooden bobbin to hold the plate firmly therein.

The plate is set into the counterbored portion 5 of the bobbin with its lower face flush with the lower end of said bobbin. 85 The whirl is preferably made of metal and on its upper face is formed a plurality of comparatively fine teeth to correspond in form and number to properly engage those of the plate in the bobbin.

It is obvious by this construction that the life of the bobbin is greatly increased by inserting this toothed metal plate into its lower end, and also that by the construction of these teeth that said bobbin may be dropped over the spindle and that these teeth thus arranged will engage those of the flying whirl and at once commence to rotate the bobbin without the necessity of first slowing down the whirl to engage the same.

The device is extremely simple, practical and efficient, and is a labor saver, and by its use the production of the spinning and twisting machine is greatly increased.

Having thus described my invention, what 105 I claim as new and desire to secure by Letters Patent, is:

In combination with the circular whirl having a bore and a plurality of teeth formed on its upper edge, a bobbin having a body 110

portion and an integral enlarged annular base, said bobbin having a gore which extends through its entire length and having a counterbored portion which extends for a distance in said base and which is of the same diameter as said whirl body, a metal plate of considerable thickness equal to the depth of said bobbin counterbored portion having a central bore and a flat top face and 10 having the edges of its periphery at right angles to said top face, said plate on its under face being counterbored to form a downwardly projecting rim, teeth on said rim, and

integral upwardly projecting spurs formed on said top face of the plate at points intermediate the bore and periphery of said plate, said plate having a driving fit with the walls formed by said counterbored portion of the spool base. 15

In testimony whereof I affix my signature 20 in presence of two witnesses.

JOSEPH W. COLLINS.
